SLIDE FASTENER

Harold J. Reiter, Chicago, Ill.

Application April 24, 1933, Serial No. 667,639

15 Claims. (Cl. 24—77)

This invention relates to separable stud and socket fasteners and particularly, to the socket portion thereof.

My invention contemplates the provision of a 5 slidable spring-pressed socket slide adapted to engage a cooperating stud and to lock the stud against a relatively stationary lug, whereby disengagement of the stud from the socket is normally prevented until the spring-pressed slide 10 is first intentionally moved. My invention further contemplates the provision of a socket adapted to lock a stud in place in such a manner that the stud may be quickly and easily released on the deliberate manual manipulation of the final 15 ger piece provided for that purpose.

My invention further contemplates the provision of a simple, efficient but inexpensive socket adapted for use with a variety of studs of different types and in connection with a variety of articles such as straps, belts, brief-cases, shoes and other leather goods as well as in connection with automobile curtains, or a great number of other articles wherein a releasable locking socket is desirable.

The various objects of my invention will be clear from the description which follows, and from the drawing, in which,

Fig. 1 is a top plan view of my improved fastener as it appears applied to a belt or strap slide.

Fig. 2 is a front elevation of the same.

Fig. 3 is a vertical section of the same, taken on the line 3—3 of Fig. 1.

Fig. 4 is a bottom plan view of the same, the cooperating stud being shown partly in section.

Fig. 5 is a similar view of a modified form of the same, the stud, however, being omitted and the movable parts being shown in their limiting positions.

Fig. 6 is a top plan view of a modified form of my invention as it appears applied, for example, to the curtain of an automobile.

Fig. 7 is a horizontal section, taken on the line 7—7 of Fig. 8.

Fig. 8 is a vertical section of the same, taken on the line 8—8 of Fig. 6.

Fig. 9 is a front elevation of the same before the application thereof to the curtain, and showing the parts in position of assembly to the curtain.

Fig. 10 is a top plan view of a modified form of the slide member, usable in connection with Figs. 6 to 9 inclusive.

Fig. 11 is a similar view of another modified 55 form of the slide member.

Fig. 12 is a top plan view of one form of the plate usable in connection with the socket shown in Figs. 6 to 9 inclusive.

Fig. 13 is a vertical section of the stud and securing eyelet therefor in their unsecured positions, and adapted for use in that form of my invention shown in Figs. 1 to 4 inclusive.

Fig. 14 is a similar view of the same, the eyelet, however, being assembled with and forced into the cooperating stud therefor.

Fig. 15 is a similar view of another form of the stud, wherein the separate securing eyelet has been omitted and an eyelet portion formed integral with the stud.

In that practical embodiment of my invention 70 illustrated by way of example and referring particularly to Figs. 1 to 5 inclusive, I have shown my invention applied to a strap or belt 20. The strap carrying the socket is intended to be detachably fastened to another article as 21 carrying the 75 stud 22, adjustment of the effective length of the strap being obtained by moving the socket along the strap to the desired point. It will be understood that the strap may form part of a variety of articles in which such straps are used, such as 80 brief cases, shoes or other articles of clothing or leather goods.

As shown in Figs. 13 and 14, the stud, designated generally by the numeral 22, may be provided with a rounded head 25 including the centrally 85 depressed anvil portion 24, a neck 26, and a bottom flange 27. The bottom flange rests on one face of the usually flexible article 21 to which the stud is to be secured. For securing the stud in place, the hollow eyelet 28 is forced through the material, as through the aperture 29 thereof, whereupon the upper end 30 engages the anvil portion 24 and is spread or flared, and until the eyelet flange is forced into engagement with the under face of the article 21. As will be later seen, 90 the head 25 is preferably made of comparatively little height, less than that of the neck 26, to reduce to a minimum the resulting height of the socket.

As shown in Fig. 15, however, the stud 32 may terminate in an eyelet portion 33 of slightly less diameter than that of the neck, in which case the anvil portion may be omitted. The eyelet may be forced through the article 21 and flanged over on the under side thereof in a manner which will be obvious to those skilled in the art and hence need not be described in detail. It need merely be said that the shoulder 34 serves to engage one face of the article while the flared portion of the eyelet 33 engages the opposite face, 100 105 110

and that a suitable washer may be interposed, if desired, between the eyelet portion and the article in an obvious manner.

Referring again to Figs. 1 to 5 inclusive, where-
5 in I have shown my invention applied to a slide member, the slide member 35 is preferably made of sheet material such as sheet metal, and is preferably provided on its top with the spaced trans-
10 verse slots 36 and 37, through which the strap or belt 29 may be passed. Depending from the edges of said slide member and preferably integral with the slotted top are the spaced sides 38 and 39. Each of said sides is provided with a suitable slot as 40 which are aligned with each other, and
15 through which a projecting part of the socket slide 41 extends to a point beyond the remainder of the socket so as to be easily accessible to the user.

Each of the projections 42 and 43 of the socket slide pass, respectively, through one of the slots 40, and each is provided preferably with an enlarged terminal or finger piece as 44, preferably bent upwardly parallel to the adjacent side of the slide member, whereby the socket slide may be moved longitudinally relatively to the slots 40 in the slide member 35. It will be seen that the upper and lower walls of said slots serve to guide the socket slide in its movement and to limit said movement in both directions.

Normally, however, the socket slide is urged 30 toward the left, as viewed in Figs. 1 to 5, by means of a suitable spring. In Figs. 3 and 4, I have shown the spring 45 as preferably made of a plurality of turns of spring wire, though it will be understood that as many turns as may be found convenient may be used, if desired, as shown by the spring 46 in Fig. 5, or that any other suitable type of spring may be used. The end portion 47 of the spring 45 is preferably made straight, and is retained in the loop 48 formed 40 at the end of the socket slide. The other end 49 of the spring 45 is similarly made straight, and is inserted into the loop 50, bent downwardly and inwardly from the material of the slide member, being preferably formed from the material removed to form the slot 36. The springs 45 and 46 each tend to expand longitudinally and thereby urge the socket slide 41 toward the left, as has been hereinbefore indicated.

It will be understood that in place of the 50 single loop 48 at one end of the socket slide, a plurality of loops as 51 and 52 (Fig. 5) may be substituted, if desired, and that the same change may be made in the loop 49 of the slide member 35. The socket slide is further provided with a substantially semi-circular edge or wall 53, which is adapted to engage underneath the head 25 of the stud and to contact with the neck 26 thereof and thereby to aid in preventing detachment of the stud, as shown in Figs. 3 to 5 inclusive, the wall 53 forming part of the edge of an opening or aperture 54 in the socket slide.

The material to the left of the edge 53 and transversely beyond the ends thereof, is removed from the socket slide to form the opening 54 and to provide a space into which the head 25 of the stud may enter freely when the socket slide has been moved toward the right. It will be understood, however, that the material need not be completely removed, as for example, is indicated in Fig. 11. In order, however, to lock the stud in place after it has been passed through the opening 54, a suitable lug is provided to engage the stud and to cooperate with the wall 53.

As shown best in Figs. 3 to 5 inclusive, said lug 78 takes the form of a projection 55, extending

downwardly from the slide member 35 and preferably formed from the material removed to form the slot 37. It will be seen that in order to lock the stud in place, the finger piece or pieces 44 may be moved toward the right against the action of the spring 45 (or 46) a sufficient distance to allow the head 25 of the stud to enter freely the opening 54 between the lug 55 and the wall 53, after which the finger piece is released. The spring thereupon moves the socket slide 41 toward the left, causing the wall 53 to engage underneath the head of the stud and to force the stud into firm contact with the lug 55. The stud is thereby locked in place against axial detachment from the socket. However, if desired, the stud may be detached by a twisting movement in one direction, whereupon the curved head, by its engagement with the wall 53, acts as a cam to force the socket slide toward the right against the action of the spring connected thereto a sufficient distance to permit the stud to pass. Or the stud may be twisted in the opposite direction to remove it first from the lug 55 and thereby to permit removal of the stud from the socket, the socket slide being yieldable. Or, the finger pieces 44 100 may be manipulated by the user by movement thereof toward the right to further open the effective space between the socket slide and the lug and thereby to release the stud for quick removal.

Should it be found advisable, however, to lock 105 the stud against detachment from the socket, and against both an axial pull and against a twisting movement, the lug 55 may be made sufficiently long to engage the neck 26 of the stud underneath the head 25 whereby the stud can be de- 110 tached only if the socket slide 41 is first moved toward the right by means of the finger pieces 44. Suitable prongs as 56 preferably bent upwardly from at least one edge of a transverse slot as 37 in the slide member 35 serve to engage the belt 115 or strap passed through the slots 37 and 36 and to secure the slide member in the position in which it is adjusted on the belt.

In that form of my invention shown in Figs. 6 to 9 inclusive, my invention has been applied 120 to the curtain 60 of an automobile, whereby the curtain may be detachably secured to the body portion 61 of the automobile. A suitable stud as 62, shown in the form of a screw stud may be used to cooperate with the socket, or any other 125 well known form of stud heretofore used for this purpose may be substituted. In any case, the head 63 of the stud is made comparatively shallow or short, as is the neck 64, the head being preferably shorter than the neck, whereby the height of the 130 socket is reduced to a minimum.

In this form of my invention, the casing 65 is provided with a preferably flat top 66, from which depends the wall 76, a series of lugs 67 and prongs 68 projecting from the lower edge of said wall. 135 A suitable slot as 69 is made in the top 66, through which slot projects the finger piece 70. Said finger piece is preferably made integral with the socket slide 71, being formed of material removed from the socket slide, adjacent the opening 87 140 (Fig. 11), or formed from material removed from between the spaced loops 75 and 75A. The end of the fingerpiece is preferably rolled or bent over to provide a cylinder adapted for smooth engagement by the finger of the user in order that the 145 socket slide may be easily manipulated. The spring 73, similar to the springs 45 and 46, serves to urge the socket slide toward the left in the manner hereinbefore described in connection with Figs. 1 to 5.

To hold the spring, part of the material between the lugs 67 is bent into the form of the loop 74 and encloses one end portion of the spring, while the right end of the socket slide 5 is similarly bent over to form the loop 75 and to hold the other end of the spring. The casing 65 is preferably made of a single piece of material, suitably cut away at its bottom edge to form the various lugs and prongs. In order to insure proper movement of and to guide the socket slide in its movement longitudinally of the casing 65, side walls as 77 and 78 are bent upwardly from the respective side edges 79 and 80 of the socket slide and are adapted to engage that part of the respective inner surfaces of the depending wall 76 which is made parallel to the opposed edges of a slot 69.

To provide a support for the under surface of the socket slide and prevent its contact with the curtain 60, a suitable plate as 81 is provided. Said plate is provided not only with an opening 59 for the passage of the stud, but is perforated with the lug-receiving slots 82 as well as with the prong-receiving slots 83, the plate being made slightly larger than, and projecting beyond the wall 76 of the casing for that purpose. After the plate 81 has been assembled with the casing, by the passage through the perforations 82 of the lugs 67, and the passage through the perforations 83 of the prongs 63, the lugs 67 are bent preferably inwardly on to the under face of the plate to secure the parts in their proper positions. The thus assembled socket may be secured to the curtain 60 by then passing the prongs 68 through the curtain and through suitable prong-receiving perforations in the lower plate 84, which is arranged on the under surface of the curtain, and is similar to the plate 81, being provided with a similar stud-receiving opening. The prongs 68 being bent over on to the plate 84, the parts are thereby tightly drawn together and secured to the curtain, ready for the reception of the stud.

It will be noted that the socket slide 71 may be provided with an opening 72, extending to the left edge thereof and having an arcuate wall 85 adapted to engage the neck of the cooperating stud. The stud is locked between the edge 85 and a suitable lug as 86. As illustrated, the lug 86 is bent upwardly from the plate 81, though it will be understood that said lug may be otherwise formed as by being bent either from the wall 76 of the casing or from the top 66 thereof without any material change in its function or operation. In any case, the lug 86 serves to cooperate with the arcuate edge 85 of the socket slide 71 to lock the socket to the stud in the manner hereinbefore described in connection with Figs. 1 to 5.

In Fig. 11, I have illustrated the opening 87 of the socket slide 88, closed at its left end as by means of the band 89. It will be understood that in this construction, the opening 87 is nevertheless of sufficient width to permit the head 63 of the stud to pass therethrough when the socket slide is moved toward the right as by means of the finger piece loop 70, and thereby to clear the lug 86.

It will be understood that the lower plate 84 is provided with an opening similar to the openings 59 and 87 for the passage of the stud head when the parts are to be locked together. It will further be seen that the stud may be locked to the socket by a twisting movement designed to cause the head of the stud to press against the

arcuate wall or edge 85 and thereby to move said socket slide toward the right in the slot 69 and to bring the opening 72 (or 87) above the stud. After the stud has been passed into the casing the proper distance and passes the edges 85, the spring 73 becomes effective to move the socket slide toward the left and thereby to cause said edge 85 to engage the neck of the stud and to grip the stud between it and between the lug 86. Unlocking of the stud is accomplished by moving the finger piece toward the right in the manner hereinbefore indicated.

It will be seen that I have provided a simple but effective spring fastener socket designed to lock one article to another, which device is adapted to yield to a certain extent under tension put thereon so as to prevent undue stress, or binding or constriction of the various parts. It will further be seen that the parts remain locked until deliberately opened or disengaged by the manual movement of a spring-pressed movable part thereof, and that I have provided a spring fastener well designed to meet the severe requirements of practical use.

While I have shown and described certain specific embodiments of my invention, I do not wish to be understood as limiting myself thereto but desire to claim my invention as broadly as may be permitted by the state of the prior art and the scope of the appended claims.

I claim:

1. A fastener socket comprising a socket slide having an opening therein, a cylindrical loop on said slide, supporting and guiding means for said slide including a top member and depending side members, at least one of said members having a slot therein, a second loop on said means, a spring having one end straight and inserted in said second loop and its other end inserted in the loop of the slide, said spring urging said slide toward its locking position within said means, said slide being provided with a stud-engaging wall at the periphery of said opening, a finger piece on the slide projecting through said slot, and a lug on the supporting means arranged to engage a stud passed through the opening, and cooperating with said wall to lock the stud to the socket.

2. In a fastener socket, a movable spring-pressed socket slide having an opening therein for the passage of a stud provided with a head and a neck, a wall of said opening being adapted to engage the neck of said stud, an outer member for slidably supporting and guiding said slide in its movement, a cylindrical loop on the slide, a similar loop on the member, a wire spring having a plurality of turns and straight ends, each of said ends being inserted into one of the loops, and a lug on said supporting means in variable spaced relation to said wall and adapted to engage the stud, said slide and said lug cooperating to lock the stud therebetween.

3. In a fastener a movable sheet metal slide having an opening therein and a stud-engaging wall limiting the opening, a sinuous spring, a supporting member for the slide provided with an integral loop enclosing one end of the spring, means on the slide for enclosing the other end of the spring, a lug on the supporting member in spaced relation to said wall, and means including a finger piece projecting from the slide and beyond the supporting member for manually moving the slide away from the lug to permit the entrance of the stud head therebetween.

4. In a fastener, a socket comprising a pair

- of relatively movable members, one of said members being stationary, a guiding and supporting casing for said members open for the entrance of a stud, said casing carrying the stationary member and being provided with a slot having end walls and side walls, a finger piece integral with and bent from the other of said members and extending through the slot, a spring between the casing and said other member, means integral with and bent from the casing for holding and enclosing one end of the spring, and similar means on said other member for holding and enclosing the other end of the spring. 80
5. In a fastener socket, a member adapted to slide on a belt or strap and having a pair of spaced transverse slots therein to receive the belt and slotted depending sides, an apertured socket slide within the member, a finger-piece on the socket slide projecting through the slot in the side, a lug depending from the member, and a spring secured at one end to the socket slide and at the other end to the member and urging the socket slide toward the lug. 85
6. In a fastener socket, a belt-receiving member having a pair of spaced transverse belt-receiving slots therein and having depending slotted sides, an apertured spring-pressed socket slide adapted to engage substantially half the circumference of a stud, integral extensions on the socket slide each passed through a slot of the sides, and a lug carried by the belt-receiving member in spaced relation to the socket slide and cooperating therewith to lock the stud therebetween. 90
7. In a fastener slide, a movable stud-engaging member cut away at one end to provide an arcuate stud-engaging wall, a spring, means at the other end of the member securing one end of the spring to the member, a belt-receiving member having a pair of spaced transverse belt-receiving slots therein for supporting the stud-engaging member and for cooperating therewith to lock a stud engaged by said wall, integral means on the belt-receiving member for holding the other end of said spring, and a relatively stationary lug integral with the belt-receiving member and arranged in opposed relation to said wall. 95
8. In a fastener socket, a member adapted to slide on and to receive a belt, said member having a top provided with a pair of spaced transverse belt-receiving slots and having a pair of parallel sides depending from the top and integral therewith, each of said sides having an elongated slot therein, a socket slide cut away at one end to provide an arcuate wall adapted to engage a stud, a spring secured to the slide and to said member, a lug integral with said member and bent therefrom in opposed relation to said wall, and integral extensions on the slide each passed through one of the slots in the sides and extending beyond the member whereby said member may be moved away from the lug against the action of the spring to permit said stud to be inserted between the lug and the wall. 100
9. In a fastener socket, a casing having a slot in the top thereof and having depending walls, a plate arranged in spaced relation to the top and having a stud-receiving opening therein, a movable socket slide supported by said plate and movable relatively thereto, the edge portions of said slide being guided by the walls of said casing, a projection integral with and extending from the slide and passed through the slot of the casing and terminating in a finger piece beyond the casing, a lug on the plate arranged in the path of said slide, and a spring urging said slide toward said lug. 105
10. In a fastener socket, a casing having a top and depending walls, the top having a slot therein, bendable prongs projecting from the lower edges of said walls, lugs projecting from said walls between the prongs, a plate having a series of prong and lug-receiving apertures therein adjacent the periphery thereof and having a stud-receiving aperture between the prong and lug-receiving apertures, a stud-engaging member arranged in the interior of the casing and above the plate, a projection on said member extending through the slot of the casing and terminating in a finger-piece, a spring connected to the casing and the stud-engaging member, and stud-engaging means cooperating with the stud-engaging member for locking a stud therebetween, said spring urging the stud-engaging member toward said stud-engaging means. 110
11. In a fastener, a belt-receiving member having a pair of spaced transverse belt-receiving slots therein, a second member provided with a snap fastener element, means for slidably supporting the second member on the first-mentioned member, an elongated cylindrical loop on each of said members, and a spring interposed between said members, each end of the spring being inserted into and enclosed by one of said loops. 115
12. In a fastener, a casing member, an apertured fastener member slidably supported by the casing member, a pair of spaced cylindrical loops on the fastener member, a loop on and integral with the casing member, and a wire spring having one end inserted into the loop of the casing member and having the other end inserted into said pair of loops. 120
13. The combination with a belt-receiving slide member provided with a pair of spaced transverse belt-receiving slots therein, said member having slotted depending sides, of a socket slide arranged between said sides, side projections on said socket slide passing through the slots of said sides and each terminating in a finger piece, a lug integral with and depending from the top of said slide member and a spring urging said socket slide toward said lug. 125
14. In a fastener, an outer member, a second member provided with a snap fastener element, means for slidably supporting the second member on and within the outer member, an elongated cylindrical loop on each of said members, and a spring having straight ends, said spring being interposed between said members, each straight end of the spring being inserted into and enclosed by one of said loops. 130
15. In a fastener socket of the character described, relatively movable means for engaging and locking a stud therein, comprising a spring-pressed slide member having a stud-engaging wall serving as part of the periphery of an opening therein, said wall subtending an angle not over 160°, an outer supporting member for said slide, an upright curved lug on one of the members adjacent said opening and cooperating with the wall, and yieldable means for moving said slide relatively to the lug comprising a sinus spring having a pair of straight ends, means carried by the slide for receiving and enclosing one of said ends and means on a relatively stationary part of the supporting member for receiving and enclosing the other end of the spring. 135

HAROLD J. REITER.
